(57) **CLAIM**

The ornamental design for a USB ellipse LED light, as shown and described.

DESCRIPTION

FIG. 1 is a PERSPECTIVE view of the design for the USB ellipse LED light;

FIG. 2 is a TOP view of the design for the USB ellipse LED light;

FIG. 3 is a BOTTOM view of the design for the USB ellipse LED light;

FIG. 4 is a SIDE view of the design for the USB ellipse LED light;

FIG. 5 is a SIDE view of the design for the USB ellipse LED light;

FIG. 6 is a BACK view of the design for the USB ellipse LED light; and,

FIG. 7 is a FRONT view of the design for the USB ellipse LED light.

The broken line disclosure in the views represents a portion of the light which forms no part of the claimed design.
